ATTORNEY

UNITED STATES PATENT OFFICE.

CHARLES L. WAGANDT, OF BALTIMORE, MARYLAND.

DESIGN FOR A CHILD'S PLATE.

SPECIFICATION forming part of Design No. 25,140, dated February 11, 1896.

Application filed October 8, 1895. Serial No. 565,081. Term of patent 7 years.

To all whom it may concern:

Be it known that I, CHARLES L. WAGANDT, a citizen of the United States, residing at Baltimore, in the State of Maryland, have invented and produced a new and original Design for a Child's Plate, of which the following is a specification.

The design is shown in the accompanying drawings, in which—

Figure 1 is a top plan view of the plate. Fig. 2 is a view showing the sectional contour of the plate.

The essential features of the design are, first, the rim of the plate having the letters of the alphabet arranged in a circle around it and a number of figures representing lilliputian people also arranged in the same circle, the said letters and figures being placed

alternately, and, second, the circular depressed panel having the representation of a table on which is a pan, at one side of the table a barrel and a number of figures representing lilliputian people disposed in various positions, some upon the table and upon the barrel and some on the floor below the table and some climbing the table-leg.

What I claim is—

The design for a child's plate, as herein shown and described.

In testimony whereof I affix my signature in the presence of two witnesses.

CHARLES L. WAGANDT.

Witnesses:

GEO. E. TAYLOR,
W. C. JENNESS.
